UNITED STATES PATENT OFFICE.

HENRY G. VOIGHT, OF NEW BRITAIN, CONNECTICUT, ASSIGNOR TO THE RUSSELL & ERWIN MANUFACTURING COMPANY, OF SAME PLACE.

DESIGN FOR A LOCK-CASE.

SPECIFICATION forming part of Design No. 32,392, dated March 27, 1900.

Application filed March 1, 1900. Serial No. 7,026. Term of patent 7 years.

To all whom it may concern:

Be it known that I, HENRY G. VOIGHT, a citizen of the United States, residing at New Britain, in the county of Hartford and State 5 of Connecticut, have invented and produced a new and original Design for Lock-Cases, of which the following is a specification, reference being had to the accompanying drawing, forming part thereof.

10 The only figure of the drawing is a perspective view of a lock-case, showing my design.

As shown in the drawing, the face-plate is illustrated in full lines, while the body of the case, which of itself is old, is shown by broken 15 lines and need not be specifically described.

The face-plate 2 has mainly parallel side edges 3 and rounded or semicircular ends 4, as shown, with ordinary screw-holes 5, con-

centric with the said ends. At one side edge 20 there is a series of small V-shaped projections 6, the upper and lower ones of which projections are directly opposite the screw-holes 5. At the opposite side edge of the face-plate, 25 there are two like projections 7, distributed as shown, the whole forming a novel unitary design for a lock-case.

Having described my invention, what I claim as new, and desire to secure by Letters Patent, is—

The design for a lock-case, as herein shown 30 and described.

HENRY G. VOIGHT.
